UNITED STATES PATENT OFFICE.

ARTHUR BESSEY SMITH, OF EVANSTON, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SUBSTATION TELEPHONE CIRCUITS.

Application filed January 5, 1924, Serial No. 684,486. Renewed July 5, 1928.

The present invention relates in general to substation telephone circuits, but more especially to sub-station telephone circuits for automatic telephone systems; and the object of the invention is to provide a new and improved local battery anti-side tone circuit for an automatic telephone. The circuit, as illustrated herein, is especially designed for a desk telephone, but the principles of the invention are applicable also to a wall telephone.

Having set forth the object and scope of the invention in general terms, I will now explain the circuits and apparatus involved more in detail, reference being had to the accompanying drawing, in which Fig. 1 is a wiring diagram of a local battery automatic desk telephone and bell box; Fig. 2 is a simplified circuit diagram; while Fig. 3 is a schematic diagram of the anti-side tone talking circuit.

Referring first to Fig. 2, the talking circuit as before stated is of the well known local battery type. With the receiver removed from the switch-hook, the transmitter T, the battery B, and the winding 6 of the induction coil I are included in a local circuit while the secondary windings 4 and 5 of the induction coil are bridged across the line conductors 2 and 3 in series with the balancing resistance 7. The receiver R, in series with condenser C, is connected between the line conductor 2 and the junction of induction coil windings 4 and 5. The transmitter and receiver circuits are normally open and are closed in the usual manner by the switch-hook H when the receiver is removed. Contact springs 10 and 11 are included in the receiver circuit, while contact springs 8 and 9 are included in the transmitter circuit.

For receiving incoming signals the ringer M is provided, which is normally bridged across the line independent of control by the switch-hook and is in series with the condenser C'.

Associated with the lower side of the line is a subscriber's impulse sender, or calling device, which is indicated by the reference character S. This sender may be of the type which is shown and described on pages 34 and 35 of "Automatic Telephony" by Smith and Campbell, published by the McGraw-Hill Book Company. It comprises essentially a pair of impulse springs 15 and 16

which are controlled by a cam (not shown) through the medium of a finger hold dial (not shown) and three shunt springs 12, 13 and 14, together with suitable means for retaining these springs in the position shown in the drawing when the calling device is not in use, and for causing all three springs to come into engagement with each other when the calling device dial is turned from its normal position. The impulse springs 15 and 16 are connected in series with the lower line conductor 2 and their function is to produce momentary interruptions of the line circuit for the purpose of operating the central office switches. The function of the shunt springs 12, 13 and 14 is to short circuit or shunt the receiver R and the balancing resistance 7 while the calling device is being operated to transmit impulses. To accomplish this spring 12 is connected to one side of the receiver, spring 13 is connected to the junction of the compensating resistance and winding 5 of the induction coil, while spring 14 is connected to impulse spring 15 which in turn is connected to the other side of the receiver, and it will be evident that with the springs connected in this manner, when they are brought into engagement the receiver and resistance 7 will be short circuited as stated.

In Fig. 1 the circuits have been drawn out in detail, corresponding parts being indicated by the same reference numerals as in Fig. 2. The apparatus at the right of the drawing, comprising the transmitter T, the receiver R, the switch-hook H, and the calling device S, constitutes the desk telephone proper; while the apparatus at the left of the drawing and comprising the ringer M, the condensers C and C', and the induction coil I is separate from the telephone and in accordance with the usual practice is located in the bell box. The telephone is provided with a terminal strip P in the base thereof, and the bell box is provided with a terminal strip P'. The various circuits are completed by means of a cord which connects the two terminal strips, and which, it will be observed, comprises five conductors. The line extending to the exchange is connected at the terminal strip P' as illustrated in the drawing.

The operation of the substation circuit is as follows: When the receiver is removed to

initiate a call, the switchhook contact springs 9 and 10 come into engagement with contact springs 8 and 11, respectively, whereby the transmitter and receiver circuits are closed 5 and the secondary winding of the induction coil is bridged across the line in series with the resistance 7. Assuming that the line terminates at the exchange in the usual line switch, the closure of the bridge at the substation, the closure of the line relay 10 station completes the circuit of the line relay of the line switch, which therefore operates to extend the line to a numerical switch or first selector. The calling subscriber now manipulates the calling device dial to produce 15 a series of interruptions for directively controlling the first selector by means of its line relay.

Considering a little more closely the operations which take place at the telephone during the transmission of a series of impulses, it will be noticed that as soon as the dial is turned from its normal position the shunt springs are closed together, and the substation loop is completed over a path which may be traced from the line conductor 3 by way of windings 4 and 5 of the induction coil I, shunt springs 13 and 14, impulse springs 15 and 16, and the switchhook springs 11 and 10 to the line conductor 2. It will be seen from this 20 that the resistance 7 is excluded from the switch control, or impulse transmitting circuit, during the time that the calling device is in operation and is included again in the bridge across the line only when the calling device dial returns to its normal position. At the same time, the receiver R is short circuited by way of shunt springs 12, 13 and 14. This latter operation takes care of the usual requirement of silent operation; in other words, 25 with the receiver short circuited the subscriber is not annoyed by hearing the clicks in the receiver, caused by the interruptions in the line circuit.

To continue, the first operation of the calling device brings about the operation of a first selector switch at the exchange, and succeeding operations of the calling device will now result in the operation of additional switches until the connection is finally completed to the line of the called subscriber, it being understood that all of the switches are provided with controlling relay bridges which, with the exception of the bridge in the last switch, are successively cut off from the line after their associated switches are operated.

The connection having been completed, conversation may be held as desired, the talking circuits functioning the same as usual in such cases, except that the side tone in the subscriber's receiver is eliminated or greatly reduced when he talks in the transmitter, as will be more fully explained hereinafter. The receiver is replaced at the end of the conversation, the transmitter and receiver circuits are

broken at the switchhook contacts, and further flow of direct current through the substation is prevented. As a result all the switches used in the connection at the central office are released and restored to normal in 70 the usual manner. The substation is now in condition to receive incoming signalling currents which may come in over the line conductors 2 and 3 and pass through the ringer M and condenser C, whereby the ringer is 75 actuated to advise the subscriber that he is being called.

The voice transmitting and receiving circuits are shown in schematic form in Fig. 3, which shows the condition of the circuits at 80 the substation when the dial is in its normal position and the receiver is off the switchhook; in other words, while conversation is being carried on. Since all the non-essential elements, such as the calling device, ringer, etc., are omitted in the schematic drawing, the relation between the parts shown may be perceived at once. It will not be necessary to go into a minute consideration of the operation 85 of the circuit from a strictly technical standpoint, but it may be stated, however, that when the subscriber talks in the transmitter T and produces variations in the direct current flowing in the local circuit including the battery B and primary winding 6 of the induction coil I, varying electromotive forces arise in the secondary windings 4 and 5 and produce varying currents in the secondary circuits which may be considered as comprising the two side circuits of the three wire system. One of the side circuits is composed of the line conductors 2 and 3 with the receiver, etc., (not shown) at the distant end, the winding 4, condenser C, and receiver R; while the other side circuit is composed of the compensating resistance 7, winding 5, condenser C, and receiver R. It will be observed that the receiver R and condenser C are in a conductor common to both circuits and that the currents flowing in the circuits oppose each 90 other or tend to neutralize each other in this common or neutral conductor, and that if the compensating resistance 7 is equal to the loop resistance of the line or, in other words, if the side circuits are properly balanced, practically no current will flow in the common or neutral conductor. Therefore it will be seen that, due to no current flowing through the receiver R, no side tone will be heard by the calling party. Incoming voice currents, of 95 course, divide at the substation, part flowing through the branch including the resistance 7 and a substantial part flowing through the receiver branch.

Compensating resistance 7 used is of a value 100 approximating that of the average loop resistance and this has been found to be sufficiently accurate for all practical purposes, although in special cases the value of the resistance may be more exactly adjusted, and it 105

may be supplemented by a capacity and inductance in order to closely balance the line. The resistance may be dispensed with if its value is added to the winding 5 of the induction coil I.

While the explanation might perhaps be further amplified, it is believed that the foregoing will suffice to enable the invention to be understood and used by those skilled in the 10 art. It will be seen that I have devised an especially advantageous circuit for a local battery automatic desk telephone which includes transmitting and receiving circuits of good efficiency and practically eliminating 15 side tone in the talking party's receiver.

Having described my invention, what I consider to be new and desire to have protected by Letters Patent will be pointed out in the appended claims.

20 What I claim as my invention is:

1. In a substation telephone set, a transmitter and local circuit therefor, an induction coil having a primary and two secondary windings the primary winding being connected in said local circuit, a resistance, a bridge across the two line conductors including in a series circuit said secondary windings and said resistance, a receiver and a condenser in series connected between one line 25 conductor and the junction of said secondary windings, and a calling device having a pair of interrupter springs in series with one of said line conductors.

2. In a substation telephone set, a transmitter and local circuit therefor, an induction coil having a primary winding connected in said local circuit and two secondary windings, a resistance, a bridge across the two line conductors including said secondary windings and said resistance, a receiver and a condenser connected in series between one line 30 conductor and the junction of said secondary windings, and a calling device having a pair of interrupter springs in series with one of said line conductors.

35 3. In a substation telephone set, a transmitter and local circuit therefor, an induction coil having a primary and two secondary windings the primary winding being connected in said local circuit, a resistance, a bridge across the two line conductors including in a series circuit said secondary windings and said resistance, a receiver and a condenser connected in series between one line conductor and the junction of said secondary windings, a calling device having a pair of interrupter springs in series with one of said line conductors, and shunt springs for short circuiting said resistance while the calling device is being operated.

40 4. In a substation telephone set, a transmitter and local circuit therefor, an induction coil having a primary winding connected in said local circuit, a resistance, a bridge across the two line conductors including in a series circuit said secondary windings and said resistance, a receiver and a condenser in series connected between one line conductor and the junction of said secondary windings, a calling device having a pair of interrupter springs in series with one of said line conductors, and shunt springs for short circuiting said receiver while the calling device is being operated.

45 5. In a substation telephone set, an induction coil and two secondary windings, a resistance, a bridge across the two line conductors including said secondary windings and said resistance, a receiver and a condenser connected in series between one line conductor and the junction of said secondary windings, a calling device having a pair of interrupter springs in series with one of said line conductors, and shunt springs actuated while the calling device is being operated for short circuiting said resistance and the receiver.

50 6. In a substation telephone set, an induction coil having a primary and two secondary windings, a transmitter in a local circuit including said primary winding, a resistance included in a series circuit with said secondary windings and bridged across the two line conductors, a receiver and a condenser in series relation and connected between one line conductor and the junction of said secondary windings, a calling device having a pair of interrupter springs normally in a series circuit including one line conductor, the secondary windings of said induction coil and said resistance, and shunt springs for short circuiting said resistance during the operation of the calling device.

55 7. In a substation telephone set, a line comprising two conductors leading to a central exchange, an induction coil having a primary and two secondary windings, a transmitter in a local circuit including said primary winding, a resistance approximating the resistance of said line included in series relation with said secondary windings and bridged across said line, said resistance together with one of the secondary windings of said induction coil forming one side of a Wheatstone bridge, while the other side is represented by the line resistance and the other of the secondary windings of said induction coil, and a receiver in series with a condenser connected to the neutral points of said Wheatstone bridge.

60 8. In a substation telephone set, a two conductor line leading to a central exchange, a resistance approximating the ohmic resistance of said line, a calling device having a plurality of springs actuated during its operation for directly controlling the apparatus in the central exchange over a path including two secondary windings of an induction coil bridged across said line, said springs producing circuit changes upon the cessation of the operation of said calling device, adapting said set to transmit and to receive talking currents over a path involving said secondary windings in series with said resistance bridged across the line, one of said 65 windings together with said resistance forming one side of a Wheatstone bridge, while the other side is represented by said line and the other of said secondary windings, a receiver in series with a capacitance being connected

70 75 80 85 90 95 100 105 110 115 120 125 130

to the neutral point of said Wheatstone bridge.

8. In a substation set, a line circuit, a transmitter, a receiver, a calling device having impulse springs and shunt springs, a transformer having three windings, a bridge across said line circuit including one winding of said transformer and said impulse springs, a local circuit for said transmitter including
- 5 a second winding of said transformer, a local circuit for said receiver including a third
- 10

winding of said transformer, a conductive coupling between said second and third windings, and circuit means connecting said shunt springs to maintain said substation at a constant resistance under the control of said impulse springs during the operation of said calling device. 15

In witness whereof, I hereunto subscribe my name this 3d day of January, A. D. 1924.

ARTHUR BESSEY SMITH.
